UNITED STATES PATENT OFFICE.

CHARLES E. ADAIR, OF BUFFALO, NEW YORK, ASSIGNOR TO CYPHERS INCUBATOR COMPANY, OF BUFFALO, NEW YORK, A CORPORATION OF NEW YORK.

HOVER.

1,053,262.

Specification of Letters Patent. Patented Feb. 18, 1913.

Application filed May 8, 1912. Serial No. 696,022.

To all whom it may concern:

Be it known that I, CHARLES E. ADAIR, a citizen of the United States, and resident of Buffalo, in the county of Erie and State of New York, have invented certain new and useful Improvements in Hovers, of which the following is a specification.

This invention relates to hovers of the self-contained or portable type, such as are 10 adapted for use in a brooder-chamber or house without the necessity of special provision therein for heating the hover, the heating-means being contained entirely within the hover itself and above the level 15 of the floor upon which the hover may be placed.

The invention relates particularly to a hover, of the type in question, in which a lamp is employed as the heating-means, and 20 one object of the invention is to provide the brooder with a heating-device and a lamp-casing of a form which will heat the brooder-chamber effectively and at the same time provide for proper ventilation of the chamber. 25

Another object of the invention is to provide against fire risk through overheating of the lamp-casing, or any other cause; and a third object of the invention is to produce 30 a construction in which the lamp may be readily removed from the hover-chamber without disturbing the hover as a whole.

Other objects of the invention, and the features of construction by which they are 35 attained, will be set forth in connection with the following description of the illustrated embodiment of the invention.

In the accompanying drawings:—Figure 1 is a transverse, vertical, median section of 40 a hover embodying the present invention; and Fig. 2 is a horizontal section on the line 2—2 in Fig. 1, showing in detail the construction and arrangement of the lamp-casing and the lamp.

45 In the illustrated embodiment of the invention a hover-chamber of the usual form is employed, this chamber comprising a circular sheet-metal upper portion having a flat top 5 and a cylindrical wall 6, and a curtain 7 of suitable flexible material depending from the lower edge of the wall. This chamber is supported upon adjustable legs 8.

The top 5 of the hover-chamber has a wide central opening from which depends 55 the cylindrical body 9 of the lamp-casing,

the lower end of this casing being closed air- and oil-tight by means of an imperforate bottom 10. The opening in the top 5 and the upper end of the body 9 is normally closed by means of a removable cover 11, 60 which consists of a hollow sheet-metal member filled with asbestos or other material having nonconducting and fireproof qualities.

The air within the hover is heated by means of a radiator, which is in the form of 65 a shallow, wide drum 12. This drum extends outwardly all around the lamp-casing, near the upper end thereof, being in free communication with the lamp-casing. The heating-lamp may be of any ordinary or 70 suitable form, and is illustrated as of a well-known construction, comprising an oil-font 13 with a burner 16 and a chimney 17 of ordinary form.

The oil-font 13 is provided, at the top, 75 with a peripheral flange 14 which rests upon a ring 15, and this ring is connected, by means of two metal strips 18, with the cover 11. The ring and the strips, in connection with the cover, constitute means by 80 which the lamp may be raised from the lamp-casing, the cover being provided, for this purpose, with a handle 22 by which it may be conveniently lifted. The parts just described also preferably constitute means 85 for normally supporting the lamp, the oil-font being held a short distance above the bottom 10 of the lamp-casing so as to provide a space into which any oil which may leak from the lamp may collect, thus retaining the oil within the lamp-casing and 90 guarding against risk of fire from this cause.

The air by which the combustion of the lamp is supported is admitted to the lamp-casing through lateral air-openings 19, 95 which are protected by wire-gauze, this gauze having a mesh sufficiently fine to prevent the passage of flame through the air-openings. The heated products of combustion from the lamp, after their passage 100 through the radiator as hereinafter described, are finally conducted from the lamp-casing through a vent-pipe 20 which passes upwardly through the cover 11, and this pipe is also provided with a fire-screen 21 of 105 wire-gauze.

The temperature of the cover is regulated by means of an opening in the top 5, controlled by a damper 23 of ordinary form, this damper being automatically opened and 110

closed through a mechanism comprising a lever 24 and a rod 25 connecting the damper with a thermostat 26, which is located in the upper part of the hover-chamber.

5 The lower end of the vent-pipe 20 projects downwardly to a point substantially below the radiator 12, and by this arrangement a proper circulation of hot air within the radiator is secured. The products of 10 combustion from the lamp, issuing from the upper end of the chimney 17, strike against the lower surface of the cover 11 and then spread in all directions into the radiator and along the upper wall thereof, and as they 15 are more or less cooled by contact with the walls of the radiator they descend at the periphery of the radiator and then pass inwardly along the lower wall of the radiator, thus returning to the lamp-casing. The partially cooled gases then descend within the lamp-casing to the lower end of the vent-pipe, through which they are finally discharged. The downward extension of the 20 vent-pipe prevents the products of combustion from at once issuing through the outlet, causing them first to ascend and flow through the radiator, as just described.

The provision of air-inlet openings in the sides of the lamp-casing results in the 25 ventilation of the hover-chamber, since a constant flow of air is produced through the chamber to these openings, and the flow of this air also acts to prevent overheating of the walls of the lamp-casing, thus maintaining 30 it at a temperature which permits the chicks to nestle against the casing without injury.

By the arrangement of the lamp-casing and the radiator just described the hover-chamber is efficiently heated, while at the 35 same time the lamp is inclosed within a casing which is entirely fire-tight. When it is necessary to trim or fill the lamp this may be conveniently done by raising the cover 40 11 and the lamp from the lamp-casing; and for this purpose it is necessary only to have access to the top of the hover, the hover-chamber being in no way disturbed in the 45 operation. Since the lamp-casing terminates at or above the level of the floor or surface upon which the hover is supported, it is unnecessary to provide any opening or recess in this floor to receive the lamp-casing 50 so that the hover may be used in any closed 55 compartment and moved from place to place as convenience may require, or it may, in fact, be used in the open air, being complete in itself.

When the temperature within the hover-chamber rises above a predetermined degree 60 the thermostat 26 opens the damper 23 automatically, and permits more or less heated air to discharge from the hover-chamber, thus automatically regulating the temperature 65 within this chamber and at the same

time contributing to the ventilation of the chamber.

My invention is not limited to the embodiment thereof hereinbefore described and illustrated in the accompanying drawings, but may be embodied in various other forms within the nature of the invention as it is defined in the following claims.

I claim:

1. A hover having, in combination, a 75 hover-chamber, a lamp-casing within the hover-chamber and extending downwardly from the top of the chamber, the lamp-casing being closed at the top, a wide, shallow, annular radiator projecting horizontally 80 around the lamp-casing, near the top thereof, and closed except at the center, where it freely communicates with the casing, and a vent-pipe passing upwardly through the top of the lamp-casing near the side thereof, the lower end of the vent-pipe being at a substantial distance below the radiator so as not to receive directly the heated gases from the lamp.

2. A hover having, in combination, a 90 hover-chamber; a fire-tight lamp-casing comprising a body depending within the hover-chamber, from the top thereof, and a removable cover for the upper end of said body, the cover having an outlet for the 95 products of combustion from the lamp-chamber; and a wide, flat, radiating-drum projecting annularly and horizontally from the lamp-casing near the top thereof, the drum opening freely into the lamp-casing 100 above said outlet but being otherwise closed, and the body of the lamp-casing being closed oil-tight at the bottom but having air-inlet openings protected by wire-gauze and located above the bottom and below said 105 outlet for products of combustion.

3. A hover having, in combination, a 110 hover-chamber with an opening in the top, a fire-tight lamp-casing comprising a body depending from the top of the hover-chamber around said opening and closed at the bottom and a removable cover for closing the upper end of said body, the body having air-inlets at a substantial distance below its upper end, and a radiator in the upper part of 115 the hover-chamber and closed except at the center, where it communicates freely with the lamp-casing above the air-inlets, the lamp-casing having an outlet-opening above the air-inlets and below the radiator.

4. A hover having, in combination, a 120 hover-chamber with an opening in the top, a fire-tight lamp-casing comprising a body depending from the top of the hover-chamber around said opening and closed at the 125 bottom and a cover for closing the upper end of said body, the lamp-casing having air-openings protected with wire-gauze at a substantial distance below its upper end, a radiator in the upper part of the hover- 130

chamber communicating with the lamp-casing above the air-inlets, and a vent-pipe protected by wire-gauze and extending through said cover from a point below the 5 radiator and above the air-inlets.

5. A hover having, in combination, a hover-chamber, a lamp-casing inclosed within the hover-chamber and extending to the top thereof, the lamp-casing having a removable cover at its upper end and its lower end being imperforate and oil-tight, a radiator in the upper part of the hover-chamber communicating with the lamp-casing, and a lamp-support depending from the cover and supporting the lamp above the bottom of the lamp-casing so as to provide a drainage-space for oil.

6. A hover having, in combination, a hover-chamber with a central opening in the 20 top, a lamp-casing comprising a body depending from the top of the hover-chamber around said opening and a removable cover for the upper end of said body, the cover being provided with nonconducting material to prevent the loss of heat, and an annular radiating-drum communicating freely 25 at its center with the lamp-casing and projecting horizontally around the casing near

the top thereof, the radiating-drum being otherwise closed and the lamp-casing having 30 openings, located below the radiator, for the admission and discharge of air to permit circulation through the lamp-casing and the radiating-drum.

7. A hover having, in combination, a 35 hover-chamber with a central opening in the top; a lamp-casing comprising a body, open at its upper end and depending from the top of the hover-chamber around said opening, and a removable cover for the upper end of 40 said body; a radiating-drum communicating with the upper portion of the lamp-casing; a lamp-support depending from the cover; and a lamp carried by said support and held, thereby, above the bottom of the lamp-casing; the bottom of the casing being closed 45 oil-tight and the body of the casing being provided with an air-inlet opening protected by wire-gauze and located above the bottom and below the radiator, and being 50 otherwise imperforate and tight against air, fire and oil.

Correction in Letters Patent No. 1,053,262.

It is hereby certified that in Letters Patent No. 1,053,262, granted February 18, 1913, upon the application of Charles E. Adair, of Buffalo, New York, for an improvement in "Hovers," an error appears in the printed specification requiring correction as follows: Page 1, line 107, for the word "cover" read *hover*; and that the said Letters Patent should be read with this correction therein that the same may conform to the record of the case in the Patent Office.

Signed and sealed this 25th day of March, A. D., 1913.

Acting Commissioner of Patents.

chamber communicating with the lamp-casing above the air-inlets, and a vent-pipe protected by wire-gauze and extending through said cover from a point below the 5 radiator and above the air-inlets.

5. A hover having, in combination, a hover-chamber, a lamp-casing inclosed within the hover-chamber and extending to the top thereof, the lamp-casing having a removable cover at its upper end and its lower end being imperforate and oil-tight, a radiator in the upper part of the hover-chamber communicating with the lamp-casing, and a lamp-support depending from the cover and supporting the lamp above the bottom of the lamp-casing so as to provide a drainage-space for oil.

6. A hover having, in combination, a hover-chamber with a central opening in the 20 top, a lamp-casing comprising a body depending from the top of the hover-chamber around said opening and a removable cover for the upper end of said body, the cover being provided with nonconducting material to prevent the loss of heat, and an annular radiating-drum communicating freely 25 at its center with the lamp-casing and projecting horizontally around the casing near

the top thereof, the radiating-drum being otherwise closed and the lamp-casing having 30 openings, located below the radiator, for the admission and discharge of air to permit circulation through the lamp-casing and the radiating-drum.

7. A hover having, in combination, a 35 hover-chamber with a central opening in the top; a lamp-casing comprising a body, open at its upper end and depending from the top of the hover-chamber around said opening, and a removable cover for the upper end of 40 said body; a radiating-drum communicating with the upper portion of the lamp-casing; a lamp-support depending from the cover; and a lamp carried by said support and held, thereby, above the bottom of the lamp-casing; the bottom of the casing being closed 45 oil-tight and the body of the casing being provided with an air-inlet opening protected by wire-gauze and located above the bottom and below the radiator, and being 50 otherwise imperforate and tight against air, fire and oil.
